UNITED STATES PATENT OFFICE.

JOHN C. FEBIGER, JR., OF NEW ORLEANS, LOUISIANA.

WATER-CLOSET SEAT.

SPECIFICATION forming part of Letters Patent No. 543,180, dated July 23, 1895.

Application filed February 13, 1895. Serial No. 638,812. (No model.)

To all whom it may concern:

Be it known that I, JOHN CARSON FEBIGER, Jr., a citizen of the United States, residing at New Orleans, in the parish of Orleans, State of Louisiana, have invented a new and useful Improvement in Water-Closet Seats, of which the following is a specification, reference being had to the accompanying drawings, forming a part thereof, in which—

10. Figure 1 represents the top of the seat and a fragment of the lid in closed position, and Fig. 2 shows a vertical section of the seat as it appears with the lid down.

The object of this invention is to provide a water-closet combining the properties of comfort and cleanliness. I attain these objects by the combination illustrated in the accompanying drawings.

15. *a* represents the base-plate, comprising a portion of the seat, which is made in one piece of porcelain, enameled cast-iron, nickel-plated brass, marble, stone, or any material impermeable to the substances that are deposited in closet-bowls in their ordinary use. This base-plate has the usual seat-opening, and is recessed on its upper face from the front to a point at or near the rear of said opening, shoulders *a'* being formed between the front and rear portions of the face.

20. *b* represents an insertion or rim of wood, compressed paper, or other material that is a poor conductor of heat, which covers that portion of the seat which comes in contact with the body and limbs, being the front and sides of said opening. This non-conductive rim does not extend across the back of the opening, but leaves that composed wholly of the non-absorbent material. This is important, as the back of the seat is the part most liable to become soiled, and when composed wholly of the impermeable material it can be easily cleaned, yet its position is such relative to the body that it does not come in contact therewith.

25. *c* represents the lid or cover for the opening in the seat, which can be made of porcelain, enameled cast-iron, nickel-plated brass, marble, stone, or other material impermeable to the substances that may be deposited in closet-bowls in their ordinary use, but pref-

erably of the same material to match the portion of the seat represented by *a*.

d represents one of as many screws as will be necessary to fasten together securely and tightly the material represented by *a* and *b*. 55 These screws pass through holes left for that purpose in the material forming that part of the seat represented by *a*.

e represents rubber bumpers, which may be attached to lid and seat wherever required 60 by expansion-screws set in holes cast or molded in the material of which the seat and lid may be made.

f represents a tail or fastening piece, which is made of same material of which portion of 65 seat represented by *a* is made. On the tail or fastening piece, which is attached to the seat, there will be holes cast or molded in such position and such number as may be necessary to fasten the tail-piece to hinge-brackets, 70 wall-brackets, or other invention that may be called for, as the shape or class of closet-bowl to be used may demand. These holes may be cast or molded through the tail-piece for bolts, or may only be cast or molded three-fourths (more or less) of the way through for use of expansion-screws.

The tail-piece, seat, and cover may be of any shape, but preferably of the shape shown in the accompanying drawings, and may be 80 made to fit any style of closet-bowl.

I claim—

1. A water-closet seat consisting of a non-porous base plate having the usual opening and being recessed on its upper face from the 85 front to a point near the rear of said opening, a permanent nonconductive lining disposed on the recessed portion of said base plate.

2. A water closet seat composed of a base plate composed of impermeable material and having the usual opening, and a permanent rim composed of nonconductive material and disposed at the front and sides of said opening, the back of said opening being non-absorbent.

JNO. C. FEBIGER, JR.
